(57) **CLAIM**

The ornamental design of a robust bracket for overhead gate hardware, as shown and described.

DESCRIPTION

FIG. 1 is a front elevational view of the robust bracket for overhead gate hardware in accordance with this invention. The broken lines showing in this figure and in the following figures are for illustrative purposes only and form no part of the claimed design;

FIG. 2 is a side elevational view of the robust bracket for overhead gate hardware of FIG. 1, the opposite side view being a mirror image thereof;

FIG. 3 is a rear elevational view thereof;

FIG. 4 is a top plan view thereof; and,

FIG. 5 is a perspective view thereof. The bottom is unornamented.
